(57) **CLAIM**

The ornamental design for a dog leash handle, as shown and described.

DESCRIPTION

FIG. 1 is a top front right perspective view of the dog leash handle.

FIG. 2 is a top front right perspective view of the dog leash handle with a handle cap removed to expose a mace container. FIG. 3 is a top front right perspective view of the dog leash handle with a handle cap removed and a mace container removed from the dog leash handle.

FIG. 4 is a front elevational view of the dog leash handle with a tip and dog leash attached.

FIG. 5 is a back elevational view of the dog leash handle with a tip and dog leash attached.

FIG. 6 is a right elevational view of the dog leash handle with a tip and dog leash attached.

FIG. 7 is a left elevational view of the dog leash handle with a tip and dog leash attached; and,

FIG. 8 is a top front right perspective view of the dog leash handle demonstrating a dog waste disposal bag being removed from a flexible slit in the handle.

In the drawings, the broken lines are included only for the purpose of illustrating environment and form no part of the claimed design.

1 Claim, 6 Drawing Sheets
